(57) **CLAIM**

The ornamental design for a cartridge for lubricant feeder, as shown and described.

DESCRIPTION

1. Cartridge for lubricant feeder

1.1: Front

1.2: Right

1.3: Top

1.4: Bottom

1.5: Cross-sectional view

1.6: Referential front view

1.7: Referential top view

1.8: Referential bottom view

1.9: Referential cross-sectional view

1.10: Perspective view

1.11: Referential perspective view

Design 1: the parts shown by means of broken lines in the reproductions are not part of the claimed design; a back view is omitted since it is the same as the front view 1.1; a left view is omitted since it is the same as the right view 1.2; 1.5 shows a cross-sectional view sectioned horizontally at the center of the top view 1.3; 1.6 shows a referential front view in which the lower cap is attached to the upper cap; 1.7 shows a referential top view in which the lower cap is attached to the upper cap; 1.8 shows a referential bottom view in which the lower cap is attached to the upper cap; 1.9 shows a referential cross-sectional view sectioned horizontally at the center of the top view 1.3; 1.10 shows a perspective view of the cartridge; 1.11 shows a referential perspective view of the cartridge.

(Continued)

tally at the center of the referential top view 1.7; 1.11 shows a referential perspective view in which the lower cap is attached to the upper cap.
